(57) **CLAIM**

The ornamental design for a display package for an over-the-counter medicinal container, as shown and described.

DESCRIPTION

FIG. 1 is a perspective view of a display package for an over-the-counter medicinal container;

FIG. 2 is a perspective view from the back side of the display package shown in FIG. 1;

FIG. 3 is a front view thereof;

FIG. 4 is a rear side view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof, shown with an over-the-counter medicinal container in broken lines.

The broken lines showing a medicinal container in FIG. 9 illustrates environmental structure. All other broken lines illustrate portions of the display package for an over-the-counter medicinal container. The broken lines form no part of the claimed design.

1 Claim, 7 Drawing Sheets
